UNITED STATES PATENT OFFICE.

HALFDAN A. STEEN, OF MILWAUKEE, WISCONSIN, ASSIGNOR TO ALLIS-CHALMERS MANUFACTURING COMPANY, OF MILWAUKEE, WISCONSIN, A CORPORATION OF DELAWARE.

CIRCUIT-CONTROLLER.

1,279,780.

Specification of Letters Patent. Patented Sept. 24, 1918.

Application filed July 25, 1914. Serial No. 853,163.

To all whom it may concern:

Be it known that I, HALFDAN A. STEEN, a subject of the King of Norway, residing at Milwaukee, in the county of Milwaukee and 5 State of Wisconsin, have invented a certain new and useful Improvement in Circuit-Controllers, of which the following is a specification.

This invention relates in general to apparatus for completing and interrupting electrical circuits, and has particular relation to apparatus of this class used for controlling motors and of such construction as to eliminate the danger of arcs, formed on 10 the interruption of the circuit, being communicated to surrounding objects or to the atmosphere which may contain particles of an inflammable or explosive nature.

It is an object of this invention to provide 20 a circuit-controlling apparatus of improved construction, which is comparatively simple in design and efficient in operation.

It is a further object of this invention to provide an inclosed circuit-controlling apparatus of improved construction in which the active fixed and movable circuit-breaking parts are capable of being readily removed from the inclosing receptacle for inspection and repairs.

30 It is a further object of this invention to provide a circuit-controlling apparatus of improved construction, which is capable of either manual operation or of being operated automatically in response to certain 35 conditions of the circuit to be controlled.

These and other objects are attained by this invention, the various novel features of which will appear from the description and drawings, disclosing one embodiment 40 of such invention, and will be particularly pointed out in the claims.

In the accompanying drawings:

Figure 1 is a vertical section through a circuit-controlling apparatus embodying 45 this invention, with the parts shown in such position as to complete the circuit, the section being taken on the line 1—1 of Fig. 3.

Fig. 2 is a view similar to Fig. 1, the parts being shown in circuit-interrupting position.

50 Fig. 3 is a vertical section along the line 3—3 of Fig. 1.

Fig. 4 is a diagrammatic view showing the circuit connections between a supply line and a translating device and the operative 55 parts of a circuit-controlling apparatus,

embodimenting features of this invention, connected to the line to control the translating device.

As shown in the drawings, a receptacle 4 is provided with a lining of insulating material 5 and a removable cover portion 6, here shown as of arched cross-section. On shouldered portions 7, 8 formed at intermediate portions of the side walls of the receptacle, are supported bars 9, preferably of insulating material, which are secured in position by bolts 10 threaded into portions of the receptacle.

Terminal contacts 12, of approximately U-shape, having spaced horizontal portions 13, 14 and a vertically disposed connecting portion 15, are mounted on the bars 9, as by means of bolts 16 passing through the bars and the horizontal portions 13 of the contacts, the heads of the bolts being disposed beneath the bar. The contacts are held in place against the bars by nuts 17 on the bolts 16, and the portions 14 are held spaced from the portions 13 by sleeves 18, preferably of conducting material, disposed on the bolts 16 between the nuts 17 and the portions 14. Extending portions 21 on the parts 14 are bent up and over parallel to the portions 14, and in spaced relation thereto, so that the end portions of line 85 terminals 23 may be received between the parts 14 and 21. Nuts 24 on the bolts 16 hold the line terminals and contacts 12 in position, with the horizontally disposed portions thereof properly spaced apart.

90 The side walls of the receptacle 4 are provided with openings in which are inserted insulated bushings 27 of a size to snugly embrace flexible connections to the line terminals 23. In the type of switch shown, three contacts 12 are disposed in alinement on each side of the receptacle, each contact on one side being arranged opposite a corresponding contact on the other side.

95 Mounted on the cover portion 6 are a plurality of spaced rods 32, these rods being shown as secured to the cover by having one end secured in openings in integral extensions 28 from the cover, being secured therein, as by pins 29. These rods are secured at 100 the other end to the parts 34, being preferably threaded thereinto. These parts 34 are held spaced apart by means of a block or plate 36, preferably of insulating material, the rods passing through openings in the 110

- plate and the latter resting on the ends of the parts 34, which are connected to such rods. The plate 36 is held in position on the rods 32, as by nuts 37 and washers 38.
- 5 5 Mounted on the upper side of the plate 36, along the edges thereof, and spaced apart the same distance as the contacts 12 on the bars 9, are a plurality of contacts 41, each having a vertically disposed U-shaped portion 42 opening downward, and a horizontally disposed portion 43. The contacts are held in position on the plate 36 by bolts 44, the heads 45 of which are disposed on the lower side of the plate, nuts 46 on the upper 10 side of the plate engaging the portions 43 of the contacts 41. Mounted on the plate 36 and in engagement with the contacts 42, are contacts 48. These latter contacts may be held in position by the bolts 44 which pass 15 through horizontally disposed portions of these contacts, the same being preferably disposed between the horizontal portions 43 of the contacts 41 and the plate 36. A substantially vertically disposed portion of each 20 contact 48 has a contact tip 51 mounted thereon at its lower end. It will be apparent that pairs of contact tips 51 are disposed in alignment at opposite sides of the plate 36, in the same way as are the pairs of contacts 25 41 on the upper side of the plate 36. Each oppositely disposed pair of contact tips 51 are adapted to engage contacts 53 disposed on opposite sides of a drum 54 and connected together, the drum being mounted for rotation beneath the plate 36, as through trunnions 55, integral with or secured to the parts 34 and acting as bearings for socketed 30 end portions 56 of the drum.
- The contacts 41 and 48 are preferably of 35 resilient material, the outer leg of the U portion of each contact 41 being biased outward away from the plate 36, and the contacts 48 being biased inward toward the center of said plate and the drum, and being limited 40 in such inward movement by stops 56, preferably of spring metal and suitably held in position as by being secured between the head 45 of the bolt 44 and the plate 36. The parts are so designed that when the drum 45 contacts are moved into circuit-closed position, the contacts 48 are moved outward against their normal bias, this inherent 50 resiliency of these contacts causing good engagement between the same and the contacts 55 53 on the drum.
- When the cover 6 is in place on the receptacle, the contacts 41 are in engagement with the respective corresponding contacts 12 along their vertically disposed portions, the 55 resiliency of the contacts 41 assuring a good electrical connection. It will be obvious that, by actuating the drum, the contacts thereon may be so moved as to complete the 60 circuit between oppositely disposed line terminals 23, this circuit being completed 65

through contacts 12, contacts 41, contacts 48, contact tips 51 and drum contacts 53.

Mounted for rotation in the cover portion 6, as by being suitably disposed in bearings in the portions 28, is an operating shaft 58 70 extending through an opening in the cover, or through matched openings in the cover and body portion of the receptacle, to the outside thereof. A sleeve 59 is loosely mounted on the shaft 58, being here shown 75 as disposed partly within the receptacle and partly outside thereof and having hub portions 61 and 62 adjacent the side wall of the receptacle to efficiently close the opening through the same. Integral with or secured 80 to this sleeve is an arm 63, here shown as being disposed outside of the casing. An actuating arm 64 is secured to the shaft 58, and a tension spring 65 connects this arm with the arm 63, this spring tending to draw 85 the arms 63 and 64 together. Stops 67 and 68, disposed on the outside of the casing, limit the movement of the arm 63. The spring 65 is so disposed on the arms 63 and 64 that the arm 63 is held against rotation 90 until the arm 64 has been so moved that the line joining the attaching points of the spring 65 has passed from one side of the axis of the shaft 58 to the other side, at which time the tension of the spring 65 causes a 95 quick movement of the arm 63 in the desired direction.

An arm 71 is mounted to rotate with the shaft 58, and an end portion thereof, in one position, engages behind a roller 72 pivoted 100 at the end portion of a latching lever 73. This lever may be so held as to maintain the arm 71 and shaft 58 in a certain operative position. The lever 73 is pivoted at 74 to the cover portion 6.

105 Also mounted on the cover portion 6 is a magnet 76 comprising a U-shaped core 77, one leg 78 of which passes through the electromagnet, the other leg 79 being disposed parallel thereto and outside of the magnet 110 winding, and a cross piece 81 secured to a shoulder portion 82 of the casing by screws or bolts 83. Fixed on the same pivot 74 as the lever 73 is an arm 85 carrying, at its end portion, an armature 86 for the magnet 76. This armature and also the latching roller 72 on the lever 73, through its connection therewith, are normally held away from the magnet core and the end of the arm 71, respectively, by a spring 87, secured at one end to the arm 85 and at the other end to a portion of the cover 6.

115 Integral with the lever 73 or attached to the pivot 74, is an arm 88 having a finger portion 89 extending through an opening 90 in the cover portion 6. This finger portion 89 may be operated to move the armature 86 away from the core of the magnet 76 and to move the latching roller 72 out 120 of engagement with the end of the arm 71. 130

A spring 91, secured to the shaft 58, or a part attached thereto, and to a fixed portion of the casing, here shown as being attached at one end to the integral projection 5 28 on the cover and at the other end to the arm 71, serves to oppose movement of the actuating arm 64 in one direction; and, when the parts are in the positions shown in Fig. 1 where the end of the 10 arm 71 engages behind the latching roller 72, this spring 91 serves to return the shaft 58 to normal position if the arm 71 is released from the latching roller 72. Of course, the spring 91 is of greater power 15 than the spring 65, in order to effect this operation of the switch mechanism. Integral with or secured to the sleeve 59, is an arm 93, the end of which is preferably of forked construction and is pivotally secured 20 to one end of a rod 94, the other end of the rod being secured to an eccentric pivot 95 on the end of the drum 54. It will be obvious that when the arm 63 is actuated, the bridging contacts 53 on the drum will be 25 moved into or out of engagement with the contact tips 51.

An operating rod 96 is secured to the end of the arm 64, the preferable connection being through a pin 97 on the arm 64 movable 30 in an elongated slot 98 of the operating rod. A spring 99, secured at one end to the rod 96 and at the other end to a fixed part, as the cover 6, serves to draw the rod 94 back to initial position when the switch mechanism 35 is operated and the rod 94 is relieved of actuating pressure, the slot 98 being of such dimensions as to permit such movement of the rod back to initial position without actuating the arm 64. With this 40 construction, it will be apparent that, with the switch in the position shown in Fig. 1, when the arm 71 is released from the latching roller 72, the spring 91 is capable of operating the shaft 58 and arm 64 to such 45 position as permits the spring 65 to return the drum contacts to initial position.

In the diagram shown in Fig. 4, a translating device M, here shown as a motor, is connected to the supply line a, b, c, through 50 the intermediary of a controlling device embodying this invention. The circuit of the magnet 76 is shown as being connected across one phase of the supply circuit through a manually operated switch 101 and an electromagnetically operated switch 102, when 55 the motor circuit is connected to the line a, b, c. The switch 102 is operated by a coil 103 either directly in the circuit a, b, c, or supplied with energy therefrom through a 60 series transformer 104, as shown. It will be obvious that, if the contacts of the main switch are in closed position, being held therein by engagement of the end of the arm 71 behind the latching roller 72, the 65 switch may be actuated to cause a return to

initial position, either by operation of the finger piece 89, by opening the circuit of the magnet 76 at the switch 101, by opening this same circuit at the switch 102 on the occurrence of an overload, or by insufficient energization of the magnet 76 due to low voltage or a break in the circuit a, b, c. Further, the engagement between the arm 71 and the roller 72 is such that, although the latch is sufficient to normally hold arm 71, nevertheless, when sufficient force is applied to the operating rod 96, the arm 71 can be drawn out of engagement with the roller 72, this force being sufficient to overcome the attraction between the parts of the magnet 76. 70 75 80

The circuit of the magnet 76 is preferably connected across a phase of the supply circuit at the contacts 41 on the plate 36. With such connections, it will be obvious that the magnet 76 and its connections are 85 wholly independent of any of the fixed connections from the supply line or the motor. While the hand-operated switch 101 and the electromagnetically operated switch 102 are not shown as part of the structural disclosure of Figs. 1, 2, 3 it will be obvious that these switches may be suitably disposed and attached to the cover portion 6, either inside or outside of the same, and that the operating magnet 103 of the switch 102 may be 90 95 suitably connected to the proper contacts 41 on the plate 36, so as to permit simultaneous removal of the switches and the connecting means between the same and the circuits that they control. 100

The casing 4 is provided with an angular bracket 106, through which the same may be suitably supported on a wall or post, with the operating parts 63, 64 and the spring 65 clear of the supporting structure. 105 The cover 6 is provided with a downwardly projecting lip 107 about its lower edge to protect against the entrance of moisture. A drain-opening 108, normally closed by a suitable plug, may be provided at the bottom of the casing 4. 110

With the parts in the position shown in Fig. 2, the circuit is open between the line a, b, c and the motor M. To put the motor into operation, the actuating rod 96 is moved 115 to the left, the right hand end of the slot 98 engaging with the pin 97 on the arm 64 and causing anti-clockwise movement thereof. When this arm has been moved to such an extent that the line between the points 120 of attachment of the spring 65 to the arms 63 and 64 passes beyond the center of the shaft 58, the spring 65 being under considerable tension at this time, the arm 63 is quickly moved to the position shown in Fig. 125 1, being limited in such movement by engagement thereof with the stop 68. Movement of the arm 63 causes the actuation of the drum 54, through the sleeve 59, arm 93 and connecting rod 94, to cause the bridging 130

contacts 53 to engage with the contact tips 51. The circuit between the line *a*, *b*, *c* and the motor *M* is now closed, the connection being through line terminals 23, contacts 12, 5 contacts 41, contacts 48 and 51, and bridging contacts 53 of the drum.

When the arm 63 is operated by the spring 65, the arm 64 is also drawn to its limit of movement, as shown in Fig. 1, 10 movement of the arm in this direction being limited either by engagement with the right hand end of the slot 97 in the rod 96, the latter being drawn back to initial position as soon as it is relieved of actuating pressure, 15 or by engagement with a fixed stop, not shown; or again, this movement might be limited by the action of the spring 65 which may be so designed that movement beyond the position shown in Fig. 1 would act to 20 compress the spring.

The motor circuit may be interrupted by actuation of the rod 96, if sufficient force is applied thereto to cause the release of the arm 71 from the latching roller 72, or by 25 the release of this latch through the finger piece 89, permitting the spring 91 to return the parts to initial position. It will be obvious that, as soon as the motor circuit is completed at the drum contacts, the magnet 30 76 is energized, causing the attraction of the armature 86 and the movement of the latch roller 72 to a position to retain the arm 71. The magnet may be deenergized by opening 35 the circuit thereof at the switch 101 or at the switch 102, on the occurrence of an overload on the circuit, or on the occurrence of low voltage on the line, permitting the spring 87 to withdraw the armature 86 and the latching roller 72 from the path of the 40 arm 71, and permitting the spring 91 to return the contact parts to initial, circuit-open position.

When the switch parts are to be inspected, the cover 4 and its attached operating mechanism are lifted bodily from the receptacle 45 4, these parts being then wholly exposed and readily accessible for inspection or repairs. It will be obvious that all the operating parts of the controller are so attached to the 50 movable part of the casing as to permit free inspection.

It should be understood that it is not desired to be limited to the exact details of construction shown and described, for obvious 55 modifications will occur to a person skilled in the art.

It is claimed and desired to secure by Letters Patent:

1. In a controlling apparatus, a receptacle, 60 terminal contacts mounted therein, a cover for said receptacle, a removable switch unit comprising relatively fixed and movable contacts mounted on said cover and actuating mechanism for said contacts, said relatively fixed contacts being engageable with said

terminal contacts, means for operating said actuating mechanism, and additional means for effecting the automatic operation of said actuating mechanism.

2. In combination, a receptacle, a cover 70 therefor, a switch unit mounted on said cover and depending in said receptacle when said cover is in place thereon, manually operable means for actuating said switch to closed or open position, means associated 75 with said actuating means for biasing said switch to open position, latch means comprising an element mounted on the inner side of said cover for holding said switch in closed position, an electromagnet mounted 80 on said cover on the inner side thereof and effective on sufficient energization thereof to maintain said latch in position to hold said switch in closed position, said latch being tripped on insufficient energization of 85 said magnet, and manually operable means for effecting the tripping of said latch.

3. In a controlling device, a stationary receptacle, a removable cover therefor, a switch unit mounted on said cover and disposed in 90 said receptacle when said cover is in place thereon, manually operable means for actuating said switch to closed or open position, means associated with said actuating means for biasing said switch to open position, 95 latch means including an element pivotally mounted on the inner side of said cover and operative to retain said switch in closed position, and a plurality of means for effecting the tripping of said latch to permit said 100 switch to return to open position.

4. In a controller, fixed and movable contacts, an operating shaft, an actuating arm fixed to said shaft, a member loose on said shaft and coöperating with said movable contact to actuate the same, a spring connection between said actuating arm and said member for operating said actuating arm with a snap action in either direction when moved beyond a certain position, a spring 110 opposing the movement of said shaft in one direction and capable of moving said shaft in an opposite direction, latch means for holding said shaft in a certain position against the action of said spring, and automatically operable means for tripping said latch.

5. In combination in a controller, fixed and movable contacts, an operating shaft, an actuating arm fixed to said shaft, a member loose on said shaft and coöperating with 120 said movable contact to actuate the same, a spring connection between said actuating arm and said member whereby the movable contact is operated with a snap action when the actuating arm is moved beyond a certain position, a spring for opposing the movement of said shaft in one direction, and latch means for holding said shaft in a certain position against the action of said 125 130

spring, said latter spring being more powerful than the spring associated with said actuating arm and said member whereby said movable contact is movable to open position 5 when said latch is tripped, and manually and automatically operable means for tripping said latch.

6. In a controlling device, a receptacle provided with a cover, stationary terminal 10 contacts mounted in said receptacle, switch mechanism comprising relatively fixed and resiliently supported contacts and movable contacts and actuating mechanism therefor removable as a unit from said receptacle, 15 the relatively fixed contacts being capable of limited movement and having portions engageable with said terminal contacts, and means for limiting the movement of said relatively fixed contacts, manually operable 20 means for effecting the operation of said actuating mechanism, and automatically operable means for effecting the operation of such mechanism.

7. In a controlling device, a receptacle 25 provided with a cover, stationary terminal contacts mounted in said receptacle, each of said terminal contacts comprising parallel spaced portions and a vertically disposed connecting portion, switch mechanism comprising relatively fixed and movable contacts and actuating mechanism therefor removable as a unit from said receptacle, contact means associated with said relatively fixed contacts and having vertically disposed spring portions 30 for engagement with the vertically disposed portions of the terminal contacts, and automatically operable means for effecting the operation of the actuating mechanism.

40 8. In a controlling apparatus, a receptacle, a removable cover therefor, a switch unit in said receptacle and comprising fixed and movable contacts and actuating mechanism therefor, said switch unit being held in place 45 on said cover and removable therewith, means for manually operating said actuating mechanism, and means for accomplishing the automatic operation of said actuating mechanism comprising an electromagnet 50 held in place on the inner side of said cover.

9. In a controlling apparatus, a stationary receptacle, a removable cover therefor, line terminals entering said receptacle independently of said cover, a switch unit mounted on 55 said cover and depending therefrom into the receptacle and operatively associated with said line terminals when the cover is in place thereon, manually operable means for actuating said switch to closed or open position, and automatic means for effecting the operation of said switch to open position independently of a portion of said manually operable means.

60 10. In a circuit breaking apparatus, a receptacle, a removable cover therefor, line ter-

minals entering said receptacle independently of said cover, terminal contacts connected to said line terminals, a switch unit comprising fixed and movable contacts and actuating mechanism therefor mounted on 70 said cover, said fixed contacts operatively engaging said terminal contacts when said cover is in place on said receptacle, means for effecting the manual operation of said switch actuating mechanism, and means for 75 effecting the automatic operation of said actuating mechanism.

11. In a controlling apparatus, an inclosing casing comprising a receptacle-forming body portion and a cover for said body portion, a switch unit comprising fixed and movable contacts mounted on said cover and depending in said body portion when said cover is in place, manually operable means for actuating the movable contact of said 80 switch, means for biasing said switch to one position, and means operative to retain said switch in another position and comprising a latch, and an electromagnet for operating said latch, said electromagnet and said latch 85 being mounted within said enclosure.

12. In a controlling apparatus, an inclosing casing comprising a receptacle-forming body portion and a cover therefor, a switch unit comprising fixed and movable contacts 90 mounted on said cover, means for biasing said switch to one position, means operative to actuate said switch against its bias, latch means for retaining said switch in a position other than biased position, tripping means 95 for said latch located within said inclosure, said actuating means extending to the outer side of said inclosure when said cover is in place thereon and comprising a movable member and an operating rod therefor biased 100 to one position, and an impositive connection between said member and said rod whereby said rod is permitted to occupy substantially the same position independently of the position of said operating member and 110 the condition of said switch.

13. In a circuit breaking apparatus, a receptacle, a cover therefor, line terminals entering said receptacle independently of said cover, terminal contacts connected to said 115 line terminals, a switch unit removably mounted within said receptacle and comprising fixed and movable contacts and actuating mechanism therefor, said fixed contacts operatively engaging said terminal contacts when said switch unit is in operative position within said receptacle, means for effecting the manual operation of said switch actuating mechanism, and means for effecting the automatic operation of said actuating mechanism.

14. In a controlling apparatus, an inclosing casing, a switch unit removably mounted within said casing and comprising relatively fixed and movable coöperative con- 130

acts, means for biasing said switch to one position, means operative to actuate said switch against its bias, latch means for retaining said switch in a position other than biased position, tripping means for said latch located within said inclosure, said actuating means extending to the outer side of said inclosure when said switch mechanism is in operative position within said inclosure and comprising a movable member and an operating rod therefor biased to one position, and an impositive connection between

said member and said rod whereby said rod is permitted to occupy substantially the same position independently of the position of said operating member and the condition of said switch. 15

In testimony whereof, the signature of the inventor is affixed hereto in the presence of two witnesses.
